HARMONIC CLASS C AMPLIFIER

Albert S. Harris, Fort Wayne, Ind., assignor, by
mesne assignments, to Farnsworth Research
Corporation, a corporation of Indiana

Application April 25, 1947, Serial No. 744,003

12 Claims. (Cl. 250—36)

1

This invention relates to amplifier circuits and particularly to a class C amplifier having a high efficiency.

It has long been recognized in the art that it is desirable to arrange a class C amplifier in such a manner that a small amount of heat only is developed at the plate of the amplifier tube. The amount of energy which is transformed into heat at the plate of the tube, and which must be dissipated, depends substantially upon the product of the instantaneous plate current and the instantaneous plate voltage with respect to that of the cathode. This may be easily understood because the product of the instantaneous plate current and the instantaneous plate voltage represents the kinetic energy of all the electrons which impact the plate of the tube, and this kinetic energy is substantially transformed into heat.

It will accordingly be obvious that the plate losses of a class C amplifier may be materially reduced by causing plate current to flow only during a short portion of the cycle, that is, during that portion when the plate voltage is at a minimum. It has therefore long been recognized in the art that a class C amplifier should be driven in such a manner that plate current flows only during a very short portion of the cycle. This may, for example, be effected by impressing rectangular pulses on the control grid of a class C amplifier, the pulses having a duration which is short compared to a cycle of operation. However, the drawback of this arrangement is that a large portion of the energy delivered to the plate circuit of the tube appears in the form of harmonic energy while the useful energy should appear at the fundamental frequency to which the plate circuit is tuned. This harmonic energy is due to the distortion of the plate voltage as can be shown by a Fourier analysis and is lost unless it can be stored in the condenser of the plate tank circuit and subsequently released at the fundamental frequency. The harmonic currents which flow in the inductive branch of the plate tank circuit are effectively coupled to the load, which is undesirable.

In order to decrease the plate losses it has been proposed to provide a number of tank circuits arranged in series in the plate circuit of the tube, one of the tank circuits being tuned to the fundamental frequency while the other tank circuits are tuned to harmonics of the fundamental frequency. In a class C amplifier circuit of this type the harmonic tank circuits allow the plate voltage to drop to a very low value thereby to

2

minimize plate losses and to reduce the generation of heat which must be dissipated by the plate of the tube. On the other hand, a considerable portion of the output power appears in the form of harmonic energy which cannot be utilized in the load impedance. Thus, the losses do not occur in the plate of the tube but in the tank circuits which are tuned to harmonics of the fundamental frequency. In a highly efficient class C amplifier the tank circuit coupled to the plate of the tube should have its highest impedance at the time the tube conducts space current. Furthermore, the energy which may be present in the form of harmonics of the fundamental frequency should not be impressed on the load impedance but should be transformed into useful energy at the fundamental frequency.

It is an object of the present invention, therefore, to provide a novel high efficiency class C amplifier circuit.

A further object of the invention is to provide a class C amplifier circuit having a tank circuit arranged so that its impedance is at a maximum when space current flows in the tube and where substantially all energy is impressed on the load at the fundamental frequency.

In accordance with the present invention there is provided, in a high efficiency amplifier circuit, a first and a second tank circuit. Means are provided for impressing pulses at a predetermined frequency on the first tank circuit for exciting it. Switching means such as a unilaterally conducting device are provided for conductively connecting the two tank circuits and for delivering power from the first to the second tank circuit. The conductive connection of the two tank circuits by the switching means causes the two circuits to be disconnected when the pulses are impressed on the first tank circuit. Accordingly, the two tank circuits are only connected between the occurrence of the pulses for delivering power at the fundamental frequency of the pulses from the first into the second tank circuit.

For a better understanding of the invention, together with other and further objects thereof, reference is made to the following description, taken in connection with the accompanying drawing, and its scope will be pointed out in the appended claims.

In the accompanying drawing:

Fig. 1 is a circuit diagram of a single ended class C amplifier circuit embodying the present invention;

Fig. 2 is a graph showing curves referred to in

explaining the operation of the circuit of Fig. 1; and

Fig. 3 is a circuit diagram of a class C amplifier circuit in accordance with the invention including two amplifier tubes connected in push-pull.

Referring now to Fig. 1, there is illustrated a single ended class C amplifier circuit in accordance with the invention including amplifier tube 1 having cathode 2, control grid 3 and anode 4. Cathode 2 is connected to ground, and a suitable source of grid bias voltage such, for example, as battery 5 is provided between cathode 2 and control grid 3. Control grid 3 is connected to the negative terminal of battery 5 through grid leak resistor 6. A driving source 7 is coupled between cathode 2, that is ground, and control grid 3 through coupling condenser 8. Driving source 7 may be arranged to develop a sinusoidal input wave for driving amplifier tube 1 in the manner of a class C amplifier.

In order to increase the efficiency, driving source 7 may be arranged to develop pulses such as indicated at 10 at a predetermined fundamental frequency. The width of pulses 10 determines the conduction period of amplifier tube 1. It has already been pointed out that the efficiency of a class C amplifier increases when its conduction period decreases in view of the resulting reduction of the plate losses. On the other hand, when the amplifier is driven by pulses of small width compared to a cycle of operation, the output voltage will contain energy at harmonic frequencies.

Anode 4 is connected to a suitable source of anode voltage indicated at B+ through anode tank circuit 11 which includes inductance element 12 and condenser 13 arranged in parallel. Anode tank circuit 11 has a high impedance and is tuned substantially to the fundamental frequency of the input wave which may be a sinusoidal wave or may consist of recurring pulses.

In accordance with the present invention there is provided load tank circuit 15 consisting of inductance element 16 and condenser 17 arranged in parallel. Load tank circuit 15 is preferably tuned to the fundamental frequency of the input wave. A load impedance indicated schematically by resistor 18 may be connected across the terminals of load tank circuit 15 through blocking condenser 20. Tank circuits 11 and 15 are not inductively coupled to each other.

A unilaterally conducting device such as diode 21 is provided for conductively connecting anode tank circuit 11 to load tank circuit 15. Diode 21 has a cathode 22 connected to load tank circuit 15 and an anode 23 connected to anode tank circuit 11. The other terminals of both tank circuits 11 and 15 are connected to the anode voltage supply B+ as shown. Accordingly, one terminal of the two tank circuits 11 and 15 is maintained at a fixed potential, that is, at the potential of the anode voltage supply.

The operation of the class C amplifier circuit illustrated in Fig. 1 may be explained by reference to Fig. 2. Solid curve 25 in Fig. 2 indicates the voltage of anode 4 of amplifier tube 1 plotted against time. The voltage of anode 4 varies with time substantially like a sinusoidal wave. The input wave impressed on control grid 3 of amplifier tube 1 may consist of recurring pulses 10 as illustrated in Fig. 2. Whenever the grid voltage exceeds the grid shutoff voltage, space current flows through amplifier 1 as indicated at 26 in Fig. 2. When control grid 3 is driven by pulses, the plate current also has the

shape of recurrent square topped pulses illustrated at 26.

As soon as the plate current begins to flow, the plate voltage curve 25 is depressed as indicated at 27 corresponding to the additional charge which flows into anode tank circuit 11. The voltage of load tank circuit 15 is indicated by dotted curve 28 which, as shown, is more nearly sinusoidal than plate voltage 25. An inspection of Fig. 2 shows that the voltage across load tank circuit 15 is positive with respect to that across anode tank circuit 11 during the negative portion of the cycle, and accordingly, current can no longer flow through diode 21. Thus, tank circuits 11 and 15 are effectively disconnected during substantially the entire negative portion of the cycle. Therefore, anode tank circuit 11 has its highest impedance during the time space current flows through amplifier tube 1. When tank circuits 11 and 15 are disconnected, harmonic energy is prevented from being coupled to load impedance 18, that is, to load tank circuit 15. Substantially the entire energy represented by the plate current is accordingly stored in anode tank circuit 11 during the time diode 21 is not conducting.

After the occurrence of plate current pulse 26, the voltage across anode tank circuit 11 rises again rapidly and will eventually correspond with the rising voltage of load tank circuit 15, that is, curves 25 and 28 will merge. At this point the two tank circuits 11 and 15 are again conductively connected through diode 21 and power is delivered from anode tank circuit 11 to load tank circuit 15. The energy delivered from anode tank circuit 11 to load tank circuit 15 is substantially at the fundamental frequency as evidenced by the sinusoidal shape of the voltage wave curve 28 of load tank circuit 15. Most of the energy delivered by the plate current at harmonic frequencies into anode tank circuit 11 is stored in condenser 13 of the anode tank circuit and released again at the fundamental frequency.

It will accordingly be seen that the efficiency of the amplifier circuit of Fig. 1 is substantially increased because anode tank circuit 11 has its highest impedance during the time that space current flows through amplifier tube 1. Furthermore, a large portion of the energy flowing into anode tank circuit 11 at harmonic frequencies is released again and transferred to load tank circuit 15 at the fundamental frequency.

Preferably plate tank circuit 11 is tuned to a frequency which is slightly higher than that of the input wave while load tank circuit 15 should be tuned to the fundamental frequency of the input wave. When anode tank circuit 11 is tuned to a frequency that is above that of the input wave, the voltage across the anode tank circuit will already have reached or approached the minimum at the time the plate current begins to flow which should decrease the anode losses. It is to be understood, however, that anode tank circuit 11 may also be tuned to the fundamental frequency of the input wave as is conventional.

It is to be understood that the amplifier circuit of Fig. 1 may be modulated in any conventional manner by either modulating the grid voltage or the plate voltage of amplifier tube 1.

Referring now to Fig. 3, there is illustrated a class C amplifier circuit in accordance with the present invention comprising two amplifier tubes 30 and 31 arranged in push-pull. The cathodes of amplifier tubes 30 and 31 are con-

nected to ground, and a suitable grid bias voltage is impressed between the cathodes and control grids of the two amplifier tubes by battery 32 having its negative terminal connected to the control grids by grid leak resistors 33 and 34, respectively. An input wave which may consist of pulses shown at 35 and 36 is impressed on the control grids of amplifier tubes 30 and 31 in such a manner that the two tubes conduct space current alternately. Alternatively, a sinusoidal input wave may be impressed in phase opposition on the control grids of amplifier tubes 30 and 31 in a conventional manner.

Anode tank circuit 37 is connected across the anodes of amplifier tubes 30 and 31 and comprises inductance element 38 and condensers 40, 41 having their junction point grounded. The center tap of inductance element 38 is connected to the anode voltage supply B+ through choke 42 which, however, may be omitted.

Load tank circuit 43 comprises inductance element 44 and condenser 45 arranged in parallel. The center tap of inductance element 44 is connected to B+ through choke 46 which also may be omitted, if desired. The load impedance indicated by resistor 47 may be coupled across load tank circuit 43 by two blocking condensers 48, 49. Two diodes 50 and 51 interconnect the terminals of the two tank circuits 37 and 43 for the same purpose as explained in connection with Fig. 1.

The circuit of Fig. 3 operates as follows. Assume that amplifier 30 is just conducting space current. Accordingly, diode 51 will not conduct current because the voltage at the junction point of diode 51 and load tank circuit 43 will be more positive than that between the junction point of diode 51 and anode tank circuit 37. At the same time, however, diode 50 will conduct space current because at this time the junction point between load tank circuit 43 and diode 50 will be negative with respect to that of the junction point between diode 50 and anode tank circuit 37.

When amplifier 30 ceases to conduct space current while amplifier tube 31 conducts space current, the conditions are reversed so that diode 50 will not conduct current while diode 51 is conducting. It will be understood that the circuit of Fig. 3 is not as efficient as that of Fig. 1 because diodes 50 and 51 conduct alternately so that a portion of the harmonic energy developed across anode tank circuit 37 will be impressed upon load tank circuit 43 which is not desirable. However, since condensers 40 and 41 of anode tank circuit 37 have their junction point grounded, a large portion of the harmonic energy will be stored in condensers 40 and 41 and released later at the fundamental frequency. In other words, the harmonic currents flow into either condenser 40 or 41 depending upon which condenser at that moment is connected to the tube drawing current.

Diode 21 as well as diodes 53 and 54 should have low losses so that the voltage between the plate and the cathode of the diodes may be relatively low when they conduct current. If diodes 21, 50 and 51 are of the indirectly heated type, their heater windings must be floating and connected to their respective cathodes.

While there has been described what is at present considered the preferred embodiment of the invention, it will be obvious to those skilled in the art that various changes and modifications may be made therein without departing from the invention, and it is, therefore, aimed

in the appended claims to cover all such changes and modifications as fall within the true spirit and scope of the invention.

What is claimed is:

5. In a high efficiency amplifier circuit, a first and a second tank circuit, means for impressing pulses at a predetermined frequency on said first tank circuit for exciting it, and switching means automatically operable at the frequency of said pulses for conductively connecting said two tank circuits and for delivering power from said first to said second tank circuit.
10. In a high efficiency amplifier circuit, a first and a second tank circuit, said first tank circuit having a high impedance, means for impressing pulses at a predetermined frequency on said first tank circuit for exciting it, a load impedance coupled to said second tank circuit, and switching means operable in response to the voltages of said tank circuits for normally conductively connecting said two tank circuits and for disconnecting them substantially during the time said pulses are impressed on said first tank circuit, thereby to deliver power from said first to said second tank circuit.
15. In a high efficiency amplifier circuit, a first and a second tank circuit, said first tank circuit having a high impedance, means for impressing pulses at a predetermined frequency on said first tank circuit for exciting it, a load impedance coupled to said second tank circuit, said tank circuits being tuned substantially to the frequency of said pulses, and a unilaterally conducting device for conductively connecting said two tank circuits and for delivering power from said first to said second tank circuit.
20. In a high efficiency amplifier circuit, a first and a second tank circuit, said first tank circuit having a high impedance, means for impressing pulses at a predetermined frequency on said first tank circuit for exciting it, a load impedance coupled to said second tank circuit, said tank circuits being tuned substantially to the frequency of said pulses, and a unilaterally conducting device for conductively connecting said two tank circuits and for delivering power from said first to said second tank circuit.
25. In a high efficiency amplifier circuit, a first and a second tank circuit, said first tank circuit having a high impedance, means for impressing pulses at a predetermined frequency on said first tank circuit for exciting it, a load impedance coupled to said second tank circuit, said tank circuits being tuned substantially to the frequency of said pulses, and a unilaterally conducting device for conductively connecting said two tank circuits and for delivering power from said first to said second tank circuit.
30. In a high efficiency amplifier circuit, a first and a second tank circuit, said first tank circuit having a high impedance, means for impressing pulses at a predetermined frequency on said first tank circuit for exciting it, a load impedance coupled to said second tank circuit, said tank circuits being tuned substantially to the frequency of said pulses, and a unilaterally conducting device for conductively connecting said two tank circuits and for delivering power from said first to said second tank circuit.
35. In a high efficiency amplifier circuit, a first and a second tank circuit, said first tank circuit having a high impedance, means for impressing pulses at a predetermined frequency on said first tank circuit for exciting it, a load impedance coupled to said second tank circuit, said tank circuits being tuned substantially to the frequency of said pulses, and a unilaterally conducting device for conductively connecting said two tank circuits and for delivering power from said first to said second tank circuit.
40. In a high efficiency amplifier circuit, a first and a second tank circuit, said first tank circuit having a high impedance, means for impressing pulses at a predetermined frequency on said first tank circuit for exciting it, a load impedance coupled to said second tank circuit, said first tank circuit being tuned to a frequency which is higher than that of said pulses, said second tank circuit being tuned to the frequency of said pulses, and a unilaterally conducting device for conductively connecting said two tank circuits and for delivering power from said first to said second tank circuit.
45. In a high efficiency amplifier circuit, a first and a second tank circuit, said first tank circuit having a high impedance, means for impressing pulses at a predetermined frequency on said first tank circuit for exciting it, a load impedance coupled to said second tank circuit, said first tank circuit being tuned to a frequency which is higher than that of said pulses, said second tank circuit being tuned to the frequency of said pulses, and a unilaterally conducting device for conductively connecting said two tank circuits and for delivering power from said first to said second tank circuit.
50. A high efficiency amplifier circuit comprising a class C amplifier tube having a control element, a cathode and an anode, means for impressing an input wave between said control element and said cathode, a source of anode voltage coupled to said anode, a first and a second tank circuit, each being tuned substantially to the frequency of said input wave, said first tank circuit being coupled to said anode, and switching means for normally conductively connecting said two tank circuits and for disconnecting them substantially during the time when said amplifier tube is conducting current, thereby to deliver power from said first to said second tank circuit.
55. A high efficiency amplifier circuit comprising a class C amplifier tube having a control element, a cathode and an anode, means for impressing an input wave between said control element and said cathode, a source of anode voltage coupled to said anode, a first and a second tank circuit, each being tuned substantially to the frequency of said input wave, said first tank circuit being coupled to said anode, and a unilaterally conducting device for conductively connecting said two tank circuits and for delivering power from said first to said second tank circuit.
60. A high efficiency amplifier circuit comprising a class C amplifier tube having a control element, a cathode and an anode, means for impressing an input wave between said control element and said cathode, a source of anode voltage coupled to said anode, a first and a second tank circuit, each being tuned substantially to the frequency of said input wave, said first tank circuit being coupled to said anode, and a unilaterally conducting device for conductively connecting said two tank circuits and for delivering power from said first to said second tank circuit.
65. A high efficiency amplifier circuit comprising a class C amplifier tube having a control element, a cathode and an anode, means for impressing an input wave between said control element and said cathode, a source of anode voltage coupled to said anode, a first and a second tank circuit, each being tuned substantially to the frequency of said input wave, said first tank circuit being coupled to said anode, and a unilaterally conducting device for conductively connecting said two tank circuits and for delivering power from said first to said second tank circuit.
70. A high efficiency amplifier circuit comprising a class C amplifier tube having a control element, a cathode and an anode, means for impressing an input wave between said control element and said cathode, a source of anode voltage coupled to said anode, a first and a second tank circuit, each being tuned substantially to the frequency of said input wave, said first tank circuit being coupled to said anode, and a unilaterally conducting device for conductively connecting said two tank circuits and for delivering power from said first to said second tank circuit.
75. A high efficiency amplifier circuit comprising a class C amplifier tube having a control element, a cathode and an anode, means for impressing an input wave between said control element and said cathode, a source of anode voltage coupled to said anode, a first and a second tank circuit, each being tuned substantially to the frequency of said input wave, said first tank circuit being coupled to said anode, and a unilaterally conducting device for conductively connecting said two tank circuits and for delivering power from said first to said second tank circuit.

7. A high efficiency amplifier circuit comprising a class C amplifier tube having a control element, a cathode and an anode, means for impressing an input wave between said control element and said cathode, a source of anode voltage conductively connected to said anode, a first and a second tank circuit, said first tank circuit being tuned to a frequency which is higher than that of said input wave, said second tank circuit being tuned to the frequency of said input wave, said first tank circuit having a high impedance and being coupled to said anode, and a unilaterally conducting device for conductively connecting said two tank circuits and for delivering power from said first to said second tank circuit.

8. A high efficiency amplifier circuit comprising a class C amplifier tube having a control element, a cathode and an anode, means for impressing an input wave between said control element and said cathode, a source of anode voltage, a first and a second tank circuit, each being tuned substantially to the frequency of said input wave, a load impedance coupled to said second tank circuit, said first tank circuit being connected between said source and said anode, and a diode having a cathode and an anode for conductively connecting said two tank circuits, the anode of said diode being connected to said first tank circuit, said second tank circuit being connected between said source and the cathode of said diode.

9. A high efficiency amplifier circuit comprising two class C amplifier tubes connected in push-pull, each having a control element, a cathode and an anode, means for impressing an input wave between said control elements and said cathodes to drive said tubes alternately, a source of anode potential conductively connected to said anodes, a first and a second tank circuit, said first tank circuit being coupled to said anodes, and unilaterally conducting devices for conductively connecting said tank circuits and for delivering power from said first to said second tank circuit.

10. A high efficiency amplifier circuit comprising two class C amplifier tubes connected in push-pull, each having a control element, a cathode and an anode, means for impressing an input wave between said control elements and said cathodes to drive said tubes alternately, a source of anode potential conductively connected to said anodes, a first and a second tank circuit, each being tuned substantially to the frequency at which one of said tubes is conducting space current, said first tank circuit being coupled to said anodes, a load impedance coupled to said second tank circuit, and two unilaterally conducting devices for conductively connecting said tank circuits and for delivering power from said first to said second tank circuit.

5 cuits and for delivering power from said first to said second tank circuit.

11. A high efficiency amplifier circuit comprising two class C amplifier tubes, each having a cathode, a control element and an anode, said cathodes being connected together, means for impressing an input wave between said cathodes and said control elements for alternately driving said tubes, a source of anode potential, a first and a second tank circuit, said first tank circuit having a high impedance, means for connecting said source to said tank circuits, said first tank circuit being connected between said anodes, a load impedance coupled to said second tank circuit, and two unilaterally conducting devices for conductively connecting said tank circuits and for delivering power from said first to said second tank circuit, said first tank circuit being tuned to a frequency which is higher than the frequency at which one of said tubes is conducting space current, said second tank circuit being tuned to the frequency of the current conduction of one of said tubes.

cuits and for delivering power from said first to said second tank circuit.

11. A high efficiency amplifier circuit comprising two class C amplifier tubes, each having a cathode, a control element and an anode, said cathodes being connected together, means for impressing an input wave between said cathodes and said control elements for alternately driving said tubes, a source of anode potential, a first and a second tank circuit, said first tank circuit having a high impedance, means for connecting said source to said tank circuits, said first tank circuit being connected between said anodes, a load impedance coupled to said second tank circuit,

10 and a second tank circuit, said first tank circuit being connected between said anodes, a load impedance coupled to said second tank circuit, said first tank circuit being tuned to a frequency which is higher than the frequency at which one of said tubes is conducting space current, said second tank circuit being tuned to the frequency of the current conduction of one of said tubes.
